CLAW PULLDOWN MECHANISM

Jasper S. Chandler, Rochester, N. Y., assignor to
 Eastman Kodak Company, Rochester, N. Y., a
 corporation of New Jersey

Application February 24, 1950, Serial No. 146,110

11 Claims. (Cl. 88—18.4)

1

The present invention relates to improvements in claw-type intermittent film-advancing mechanisms for handling perforated motion-picture film.

Although many types of intermittent film-advancing mechanisms for motion-picture cameras, projectors, perforators, printers, etc., have been designed, these known mechanisms possess certain disadvantages in spite of the great amount of effort and development work which has been devoted to this problem.

The primary object of the present invention is the provision of an intermittent film transport mechanism of the claw-type which possesses the following advantages strived for in the art: The mass and dimensions of the moving parts are substantially reduced to the end that high-speed operation is possible with reduced forces of acceleration, reduced rubbing velocity and, hence, reduced wear on the parts; the follower is normally held in contact with the driving cam by a spring which not only provides the force for effecting the return and film-engaging motions to the claw, but provides automatic take-up in the event of wear on the cam and cam follower surfaces, thus providing accurate positioning of the film and reduced noise of operation over a long period of time; the spring is tuned to cancel out the fundamental harmonic, and actually certain portions of the higher harmonics of the claw accelerational forces, to thereby reduce the working pressure between the cam and follower surfaces; the cam has a configuration primarily useful for apparatus other than projectors, although it could be modified for use thereon; the cam provides a pull-down angle of approximately 130° characterized by the fact that approximately one-half of this pull-down angle produces positive acceleration and the remainder produces negative acceleration with a gradual tapering off at the end position where the claw comes to a stop before being withdrawn from the film path and, as a result of which, the advance of the film is smoothly and accurately stopped at the desired end position; the top and bottom edges of the claw tip are tapered inwardly to a slight degree and the cam is so designed that the claw completely fills the perforation when moved into engagement therewith, whereby the claw has control of the film both during the positive and negative accelerating movements thereof, and there is no sawing action between the bottom claw edge and the bottom edge of the engaged perforation; an auxiliary cam and follower are provided which prevents the cam follower from accidentally leaving the driving cam due to any unusual occurrence during the engagement of the claw with the film, and which auxiliary cam takes over, in combination with the driving cam and its followers, to permit reverse operation of the claw mechanism for feeding the film in the

2

opposite direction; and guiding means are provided on said driving cam or auxiliary cam follower which cooperate with their companion parts to guide the claw laterally in a given plane of movement; and the contour of the driving cam is so designed as to eliminate any sudden changes in the acceleration of the cam-driven parts during the operation cycle.

The novel features that I consider characteristic of my invention are set forth with particularity in the appended claims. The invention itself, however, both as to its organization and its methods of operation, together with additional objects and advantages thereof, will best be understood from the following description of specific embodiments when read in connection with the accompanying drawings, in which:

Fig. 1 is a schematic showing of a pull-down mechanism constructed in accordance with one embodiment of the present invention and shown in association with a film gate and film path of any type of apparatus adapted to handle motion-picture film;

Fig. 2 is an enlarged elevational view of the pull-down mechanism showing the position the parts assume when the claw is at the top of the pull down stroke;

Fig. 3 is a view corresponding to Fig. 2 but showing the claw at the bottom of its pull-down stroke;

Fig. 4 is an enlarged view of the tip of the claw showing the configuration thereof and the position it assumes relative to the engaged film perforation when at the top of the pull-down stroke, or in the position shown in Fig. 2;

Fig. 5 is similar to Fig. 4, but showing the tip of the claw in the position it assumes relative to the engaged film perforation when the claw is at the bottom of its pull-down stroke, or the mechanism is in the position shown in Fig. 3;

Fig. 6 is a diagrammatic illustration of the path described by the tip of the pull-down claw during operation of the mechanism;

Fig. 7 is a sectional view taken substantially on line 7—7 of Fig. 2 and showing how the flanges on the driving cam guide the claw member laterally;

Figs. 8, 8-a and 8-b diagrammatically illustrate how the parts of the follower mechanism enter into the design of the spring in order to tune the spring so as to cancel out the fundamental harmonic;

Fig. 9 is an enlarged elevational view showing another embodiment of the present invention, particularly designed to permit feeding of the film in the reverse direction, as well as to prevent accidental separation of the follower surfaces from the driving cam;

Fig. 10 is a sectional view taken substantially on line 10—10 of Fig. 9;

Fig. 11 is a diagrammatic view of the cam and

follower illustrating certain dimensions referred to in the specification, comparing the contour of the cam of the present invention with the contour of a prior art cam; and

Fig. 12 shows the acceleration curves of a prior art cam and a cam modified according to the present invention.

Like reference characters refer to corresponding parts throughout the drawing.

Referring to Fig. 1, basically this pull-down mechanism operates in the same manner as conventional claw pull-down mechanisms in that the claw intermittently engages a perforation of a film "F" located in a given plane by a gate 10 above and below which loops 11 are maintained as is required with such claw-feeding mechanisms. The claw is reciprocated by a peripheral driving cam 12 which is fixed to cam shaft 13 extending parallel to, and laterally of, the film at the gate. This shaft may be rotated at a constant desired speed by any suitable mechanism including a driving wheel 14 coaxial therewith and located to one side of the film path.

Engaging the periphery of the driving cam 12 is a follower in the form of a Y, which is pivoted on a pin 16 carried on the end of an arm 17 and which arm is, in turn, pivoted on a fixed pin 18 whose axis is parallel to that of the cam shaft 13. A coiled spring "S" wrapped around pivot pin 18 has one end 19 engaging arm 17 and normally acting to move it and the follower 15 in a clockwise direction, or toward the cam. The inside edges of the two branch arms 20 and 21 of the Y-shaped follower engage the periphery of the cam and constitute follower surfaces 22 and 23 which, as indicated, may be separate hard-wearing inserts, i. e., sapphire, carboloy, etc. On the end of arm 21 is formed the film-engaging claw 24.

As will be apparent from an inspection of Figs. 2 and 3, the periphery of the driving cam 12 is completely irregular with respect to its axis of rotation. In advancing the film, the cam rotates counterclockwise and the cam and follower are so designed that both follower surfaces 22 and 23 are in simultaneous engagement with spaced points on the cam surface at all times. The cam is so formed that it, in combination with the spring "S," causes the claw tip to describe a path of the type shown in Fig. 6. The cam positively drives the claw downwardly and out of engagement with the film perforation at the end of the pull-down stroke, while the spring "S" provides the power to return the claw to the top of its stroke and then back into engagement with the successive film perforation. The opposite sides of the cam extend slightly beyond the periphery of the cam surface to constitute guide flanges 25 which overhang opposite edges of the follower surfaces 22 and 23, and thus serve to laterally guide the follower and claw in their given plane of movement. This guiding action of flanges 25 is most clearly apparent from an inspection of Fig. 7.

This cam 12 is so designed that the pull-down stroke takes approximately 130° of the cam rotation as distinguished from 60° to 72° pull-down angles normally used in the cams of claw mechanisms of this type. While this pull-down angle is not suitable for use on motion-picture projectors, wherein quick pull-down times are required, it is suitable for all other types of motion-picture apparatus including perforators, printers, cameras, etc. The advantage of this large pull-down angle is that the accelerational forces re-

quired to move the film can be reduced to one-fourth of those required for a 65° pull-down angle due to the fact that more cam movement is available to get the film up to speed, and to stop it, and this relationship varies inversely as the square of the pull-down angle. It will be apparent that this cam shape could be redesigned to give a smaller pull-down angle and thus be adapted for use on projectors, but then certain advantages of the same (so far as low accelerational forces are concerned) would be lost. Also, a skip stroke arrangement without alteration of the cam could be used for projector operation.

Of this 130° pull-down angle, approximately half thereof is used to accelerate the claw. The remainder of the pull-down angle is used to decelerate the claw so that it will come to a stop gradually at the end of its stroke and only very low inertia forces of the claw, or film, will be present and tend to carry the film past a given bottom position. The last 4 or 5 degrees of the pull-down movement take place at a very much reduced value of deceleration prior to withdrawal of the claw from the engaged perforation. This insures the film being completely stopped and accurately located at the time the claw leaves the engaged perforation. The cam surface is so designed that the characteristic curve of the acceleration forces during the entire motion has no sharp corners, as is characteristic of the Lumière, constant acceleration and other type cams, but the changes in accelerational forces, both in direction and magnitude, are smoothed out. This results in less wear in the cam and follower surfaces due to accelerational forces and appreciably reduces noise of operation. This is done by the technique of Fourier analysis and the elimination of all harmonics above the 10th.

With this cam and follower construction, the parts can be reduced in size and mass as compared with conventional claw mechanisms for doing the same job. For example, I have found that a cam approximately $\frac{3}{8}$ " long in the long dimension and $\frac{1}{8}$ " long on the short dimension, will give the advance stroke required when using a 16 mm. movie film. Reduction in overall dimensions of the cam results in reducing the rubbing velocity, and, hence, wear, between the cam and follower surfaces, while reduction in mass makes possible higher operating speeds. I have found that a claw mechanism of this type can be operated at speeds at least as high as 1950 R. P. M. for long periods of time without difficulty. An examination of the cam and follower arrangement will show that actually the cam and follower surfaces have only a two-point contact at any one position of the mechanism.

As clearly indicated in Figs. 4 and 5, the tip of the film claw 24 has its top and bottom edges 26 and 27 respectively inclined toward one another to provide a tapered film-engaging portion. This construction permits the claw to move into the engaged perforation, indicated at "F," in Figs. 4 and 5, until both the top and bottom edges 26 and 27 thereof engage the top and bottom edges of the perforation, whereby the claw has positive control of the film in both directions and, as the result of which, no impact between the edges of the perforation and edges of the claw are encountered at any time. Small amounts of pitch variation in the film are accommodated before the start of the advance stroke. I have found that if the edges 26 and 27 of the claw are inclined 4° inwardly relative to the remainder of the cor-

responding portions of the claw, very satisfactory results are obtained.

The cam and follower are so designed that at the top of the stroke the top edge 26 of the claw is horizontal and parallel to the top edge of the perforation. See Fig. 4. This means that the bottom edge 27 of the claw lies at an angle of 8° relative to the bottom edge of the perforation. At the bottom of the pull-down stroke, these conditions are reversed; namely, the bottom edge 27 of the claw is horizontal and parallel to the bottom edge of the perforation, and the top edge 26 makes an 8° angle with the top edge of the perforation. See Fig. 5. This condition makes for accurate positioning of the film in either forward or reverse direction of operation, even if the claw tip has not entered to the full depth. This rocking motion of the claw tip through 8° during the pull-down stroke does not introduce a sawing action between the bottom edge 27 of the claw and the bottom edge of the perforation, because the cam and follower mechanism are so designed that, during the slight rocking motion of the claw, the dimension "X," shown in Figs. 4 and 5, remains constant throughout the pull-down stroke of the claw. This indicates that the same point on the edge 27 of the claw which engages the bottom edge of the perforation of the claw at the top of the stroke also engages the perforation at the same point at the bottom of the stroke.

Coming now to the primary novel feature of my pull-down mechanism which distinguishes it from the prior art more than any other mentioned up to this point, I have found that certain definite advantages can be obtained by tuning the spring "S" to the operating speed of the pull-down mechanism, whatever it might be. This tuning of the spring "S" cancels out the fundamental harmonic, and actually certain amounts of the higher harmonics, in the mechanism. The result of this is that the spring actually takes care of part of the accelerations and decelerations of the spring-moved mass when operated at the specified speed with the result that the remaining forces between the cam and follower surfaces are appreciably reduced, along with a corresponding reduction in wear on the cam and follower surfaces. In fact, I have found that by tuning the spring, the forces between the cam and follower as compared to those for a low rate spring are reduced by 30 to 50 per cent, depending upon the portions of the claw stroke being considered. For instance, the forces between the cam and follower surfaces are reduced 30 per cent at the peaks in the pull-down stroke and in the return stroke; the peak forces occur at the points where the downward accelerational forces, plus the upward spring forces, are at a maximum. This reduction in accelerational forces becomes significant when it is noted that the acceleration may amount to as much as 42 g's at the film for an operating speed of 1950 R. P. M., see Fig. 12.

The tuning of this spring involves calculating the spring constant, or spring stiffness, required to vibrate the movable follower mechanism at the frequency the device is to operate and then from this constant to compute the size of spring having this desired constant. The calculation of the spring constant involves solving the following formula:

$$2\pi f_r = \sqrt{\frac{K}{M}}$$

in which f_r is the operating frequency in cycles per

second to which the spring is to be tuned; K is the spring constant referred to a given convenient point in the moving system; and M is the equivalent mass of the moving parts acted on by the spring including follower 15, arm 17, and pivot pin 16 (the mass is equal to the weight divided by "g," the standard acceleration of gravity or 386 in./sec.²) referred to the same convenient point in the moving system. After the value "K" is determined, the spring can be computed from the following formula for a cylindrical helical spring of circular cross-section, if that is the type used, as in the present instance.

$$f = \frac{Plr^2}{EI} = \frac{64Plr^2}{\pi Ed^4}$$

where

"f" is the deflection and "P" is the force, both referred to the radius "r,"
"l" is the wire length,
"E" is Youngs modulus, and
"d" is the wire diameter

In order to point out what is involved in tuning the spring of the present pull-down mechanism, with the aid of Figs. 8, 8-A and 8-B of the drawings, the calculations required for tuning a spring for a 16 mm. single frame pull-down mechanism which I have found satisfactory for operation at a frequency of 1950 R. P. M. will be shown. The follower mechanism having been designed, and being like that shown in Figs. 8, 8-A and 8-B, although these figures are obviously drawn out of scale for purposes of clarity, the first step is to find the equivalent mass of each part of the follower mechanism with reference to a given point in the moving system.

The weight of the claw member part shown in Fig. 8 and being $\frac{3}{2}$ " thick was found to be 1.574 gr.=.00347 lb. The natural frequency of the claw part was then found to be 140 C. P. M. by suspending it as a pendulum at a radius of 2.145" from the normal film plane. This center of suspension indicated at "A" in Fig. 8 was found by the intersection of lines drawn at 4° to the film plane at the top and bottom of the claw stroke which is .300" in a single frame of 16 mm. film. This point of suspension was chosen because it represents the equivalent center about which the claw tip must rotate so that the same will enter the film perforation with its inclined upper edge perpendicular to the film plane and leave the film perforation at the bottom of the stroke with its lower edge perpendicular to the film plane. The weight of arm 17 was found to be 1.97 gr.=.00434 lb. and its natural frequency when suspended at the right-hand edge of the $\frac{3}{2}$ " hole was found to be 212 C. P. M. The location of the center of gravity and its distance from the point of suspension was next determined for both the claw and the arm.

The radius of gyration "k" was then found for both the arm and claw member from the formula:

$$k = \frac{187.6}{n} \sqrt{c}$$

where

"n" is the frequency of the pendulum in cycles per minute, and

"c" is the distance of the center of gravity from the suspension point

which is derived from the formula for a gravity or physical pendulum and is

$$T = 2\pi \sqrt{\frac{k}{cg}}$$

where "T" is the period of the pendulum in seconds

For claw member

$$k = \frac{187.6}{140} \sqrt{1.687} = 1.741''$$

For arm

$$k = \frac{187.6}{212} \sqrt{.391} = .553''$$

at right-hand edge

Correcting k for arm to center of hole in arm instead of right-hand edge

$$\bar{k} = \sqrt{.553^2 + .391^2} = .391$$

where $\bar{k}$ = radius of gyration referred to center of gravity

$$k = \sqrt{.391^2 + .344^2} = .521''$$

at center of hole

Weight of pivot pin 16 connecting arm to claw member = .000328 lb.

Equivalent weight of claw member at left-end of arm 17 = $.00347 \left(\frac{1.741}{1.625} \right)^2 = .00398$ lb.

Equivalent weight of arm at left-end of arm 17 = $.00434 \left(\frac{.521}{.875} \right)^2 = .001535$ lb.

Equivalent weight of pin at left-end of arm 17 = .000328 lb.

Total = .00584 lb.

∴ Spring constant referred to left end of arm

$$from \quad 2\pi f = \sqrt{\frac{K}{M}}$$

$$2\pi \times 32.5 = \sqrt{\frac{K}{.00584}}$$

$$K = .631 \text{ lb./in.}$$

To compute a spring having the required constant, it is necessary to assume a given diameter of spring and substitute in the following formula:

$$f = \frac{Plr^2}{EI} = \frac{64Plr^4}{\pi Ed^4}$$

Assuming wire .0390" in. diameter for tuning to 1950 R. P. M.

$$\frac{l}{k} = \frac{f}{P} = \frac{l}{.631} = \frac{.64l(.875)^2}{\pi 30 \times 10^6 (.0390)^4}$$

$$l = 7.05''$$

If we allow the spring to have 5 coils, then the mean coil diameter

$$\frac{7.05}{5\pi} = .449''$$

and outside diameter = .488"

It is also necessary to calculate the maximum spring stress to determine if this is a safe value. We use the formula,

$$P = \frac{\pi d^3 S_s}{32r}$$

where S_s is tensile and compressive stress. The value P must be determined first.

Total travel at arm end =

$$.3 \times \frac{1.625}{2.145} = .238''$$

Allowing about $\frac{3}{2}''$ additional motion for initial loading of spring

$$Max P = (.238 + .094) .631 = .209 \text{ lb.}$$

Substituting this value of P in the formula and solving for S_s

$$P = \frac{\pi d^3 S_s}{32r}$$

$$S_s = \frac{32Pr}{\pi d^3} = \frac{32 \times .209 \times .875}{\pi (.039)^3}$$

$S_s = 31400$ lbs. sq. in. which is an allowable value.

Accordingly, for tuning the spring in question, the spring should have 5 turns; an outside coil diameter equal to .488"; a wire diameter equal to .0390", and about $\frac{3}{2}''$ initial spring deflection measured at arm end.

The contours of conventional cams used in film pulldown mechanisms have characteristic acceleration curves having sharp corners and sudden changes of large magnitude as evidenced by vertical lines in the solid line curve of Fig. 12. These sharp curves are the result of high harmonics being present in the Fourier analysis of the operation cycle. I have discovered that if the contour of the cam is modified to smooth out the sharp corners and eliminate sudden changes in accelerational forces without changing the path of movement of the claw from that desired, that an appreciable amount of noise and wear between the cam and follower surfaces can be eliminated.

In the following table I show the comparison of the cam contours for a conventional cam designed to give the desired path of claw travel shown in Fig. 6 and one having a contour modified according to the present invention to smooth out the acceleration curve.

Table

β	B (unmodified)	B (modified)
351	111.39	111.40
0	112.45	112.86
9	118.75	118.49
18	130.86	130.50
27	148.78	149.07
36	172.49	172.72
45	199.85	199.14
54	225.77	225.68
63	249.43	249.87
72	270.26	270.50
81	287.74	287.70
90	301.44	301.56
99	311.02	311.17
108	316.25	315.73
117	316.18	316.22

In this table:

β = Cam rotation angle relative to follower, in degrees

B = Perpendicular distance from cam axis of rotation

to left face of cam follower surface, in mils. See Fig. 11. In this table only the advance portion of the motion is shown, but the modification will extend in similar fashion throughout the 360° of rotation. The acceleration curves for these two cams are shown in Fig. 12.

The unmodified cam contour is characterized by portions having a parabolic relationship between β and B and portions of circular arcs so chosen as to provide the required film advance in the specified angle of rotation, and the remaining portions of claw travel, due consider-

70

ation being given to the fact that both followers ride on the same cam and to the arrangement which gives a minimum cam size. The modified contour is found by taking as few terms as necessary of the Fourier series for the unmodified case (10 terms for this example) in order to provide the desired claw motion without undue rounding of the corners or departure from the straight portion of the claw path shown in Fig. 6.

Cams with straight followers employing the parabolic relationship between β and B (also called constant acceleration cams since the second derivative of B with respect to β is a constant) and cams made up partly, or entirely, of circular arc segments of finite values at different radii and center locations (usually called Lumière cams) are well known. The most common cams are usually symmetrical in shape, and quite often are of constant diameter so that they will work between parallel straight followers. Such cams need not be symmetrical, however, as in the unmodified profile of the example given in the above table.

Both the "constant acceleration" cams and the Lumière cams have the advantage of being easily calculated. "Constant acceleration" cams produce a given motion with the minimum possible peak value of the second derivative of B with respect to β (for rectilinear motion of the follower, this also means minimum acceleration for constant drive shaft speed). Lumière cams owe considerable of their popularity to the fact that in the absence of cam generating and reproducing equipment they offer some simplicity of layout and construction.

Referring to Fig. 12, it will be seen that in the acceleration curve for the unmodified cam, the first or negative acceleration portion corresponds to a portion of the cam following the parabolic relation, and that the second or positive acceleration portion corresponds to a portion of the cam consisting of a circular arc. In both cases there are sharp corners and sudden changes of large magnitude. Since the forces between the claw tip and the film, and between the cam and its follower, are both directly related to the acceleration, it follows that shock loadings would exist in the unmodified case. The sudden force changes are productive of vibrational noise and wear. The situation is analogous to the sudden application of full throttle or full braking force on any moving vehicle. The sharp corners and the vertical lines of the unmodified acceleration curve are the result of high harmonics being present in the Fourier analysis of the operation cycle.

The modified curve results from the elimination of all of the harmonics above the 10th. The change in the acceleration curve is very pronounced while the actual change in the cam shape and claw path, although important, is small, see table above. Another manner of distinguishing a cam modified according to this invention from a "constant acceleration" cam or a Lumière cam is that in my modified cam no finite length of the cam surface is arcuate in shape, and each curved portion of the cam surface blends into the adjacent curved portions so that there are no sudden changes in curvature, and hence acceleration, caused by a follower passing from one portion to the next. As mentioned above, a Lumière cam is characterized by being made up either partly or entirely of circular arc segments of finite length,

whereas "constant acceleration" cams, although their surface does not include arcuate portions, are characterized by sudden changes in curvature and acceleration between successive parabolic portions.

In addition to the reduction of noise and wear, the modified acceleration curve provides the significant advantage of gradual reduction of the force near the end of the advance stroke. This reduces the tendency of the film to over-shoot or travel past the correct stopping position for a given frictional retarding force applied to the film, probably at the gate. The accuracy of film location is thereby improved, and in some types of apparatus this of considerable importance (i.e., to produce steady pictures in ciné cameras or in step printers), and it is anticipated that an even more pronounced reduction in the acceleration force near the end of the advance stroke may be desirable. It will be appreciated that in the curves of Fig. 12 only that portion of the claw travel constituting the actual pull-down stroke of the claw has been shown. This includes approximately 130° (from 350°-120°) and is indicated on Fig. 6.

Referring now to Figs. 9 and 10, a modification of the claw pull-down mechanism already described which permits feeding of the film in the opposite direction for any reason will now be described. As before, this modified mechanism comprises a Y-shaped follower 15' pivoted to the end of arm 17' by a pivot pin 16'; said arm, in turn, being pivoted at its other end to a fixed pivot 18'. The follower surfaces 22' and 23' on the follower 15' are normally pressed into engagement with a driving cam 12' by a coiled spring S', the driving cam having the same contour as in the first embodiment and alone serving to drive the film in a forward direction and withdraw the claw from the film path, while in combination with spring "S" controlling the return travel of the claw and its return stroke into the film path. Also as before, the follower includes a claw 24' adapted to engage the film perforations for driving purposes. I have also shown it as including a second claw 30 which is spaced from claw 24' by a distance equal to the frame or perforation spacing of the film and engages the perforation immediately following the one engaged by the feeding claw. This second claw 30 is provided to take over the feeding of the film in the event the claw 24' misses its intended perforation engagement for any reason, such as, irregular perforation spacing due to film splices, mutilated perforations, etc. Normally, the second claw 30 does no work whatever. Up to this point, this modification of the pull-down mechanism is the same as that first disclosed, both in structure and principle of operation.

In order to permit reverse film-feeding operation, a second cam was added to the cam shaft to work in conjunction with cam 12', the two cams being then boxed in by an addition to the follower 15' which includes a third follower surface for engaging the second cam. To this end, I have shown the second cam referred to as being two like peripheral cams 31 of the form best shown in Fig. 9 and mounted in alignment with one another on opposite sides of driving cam 12' and having the same axis of rotation as cam 12'. Branch arms of follower 15' are then joined by arcuate portion 32 lying in same plane as cam 12' and supporting arcuate follower surfaces 33 disposed to engage the peripheral cams 31. The arcuate follower surfaces 33 are each provided

with a flange 34 which overhangs the periphery of its corresponding cam 31 and cooperates with a machined or faced border 35 thereon to laterally guide the claw and follower during operation. See Fig. 10. These flanges serve the same function as flanges 25 on cam 12 in the first embodiment of the mechanism disclosed. See Fig. 7.

It is pointed out that in the normal forward feeding of the film, cams 31 and follower surfaces 33 are called upon to do nothing. Accordingly, these parts are so designed that when the device is operating in a forward direction there is a slight clearance; i. e., .001 or .002 in. between follower-surfaces 33 and cams 31, as indicated at 36 in Fig. 10. By virtue of this clearance, there is no wear between cams 31 and follower-surfaces 33 when the pull-down mechanism is operating in its forward direction and under normal conditions.

However, when it is desired to feed the film in the reverse direction, the direction of rotation of the cam shaft 13 is reversed and cams 31 and follower surfaces 33 come into engagement to positively drive the claw into engagement with the film at the bottom of the stroke and upwardly during the time the claw is in engagement with the film perforation. It will be appreciated that in this movement the forces between the cams 31 and their follower-surfaces 33 are reduced by the normal action of spring "S," which constantly tends to move the claw arm in these two directions. Withdrawal of the claw from the film path at the top of the stroke and downward movement thereof is then taken over by cam 12' engaging follower surfaces 22' and 23' on the claw member, followers 33 being removed from their cams 31, by the amount of the clearance provided between the two, due to the normal bias in spring "S."

Accordingly, when the claw mechanism is being operated in the reverse direction, the cams 12' and 31 along with their respective follower surfaces act in combination to give the desired claw movement. It will also be appreciated that the cooperation between cams 31 and their follower surfaces 33 will prevent the follower surfaces 22' and 23' from leaving the cam 12' in forward operation should any condition arise which would require more force than the spring pressure alone to hold follower surfaces 22' and 23' in engagement with cam 12'.

Cams 31 are so designed that, in reverse operation of the mechanism, the claw tip will follow exactly the same path that it does in forward operation; namely, that shown in Fig. 6. Such a cam configuration is readily obtained without calculation by deciding where the follower surfaces 33 should be and operating a claw arm of the type shown in Fig. 9 in the forward direction by only the cam 12' but with a blank of metal fixed to the face thereof in overhanging relation with one of the followers 33. As the claw mechanism is operated intermittently, the points at which the follower 33 passes over the metal blank can be scribed thereon, and then the scribed blank can be cut to shape on a milling machine. By such a procedure, a large scale master can be made in conjunction with the master already made for cam 12. From such a master cam any number duplicates can be reproduced readily and accurately on a pantograph profile milling machine, as is well known. As indicated in Fig. 10, both cams 31, as well as cam 12', along with the cam shaft 13, are preferably cut from a

single piece of stock so as to eliminate the problem of properly orienting the several parts. The hole "H" shown in each of the cams 31 and 12 in Figs. 9 and 10 is for the purpose of reducing the mass of these parts.

While cams 31 appear to be regular in shape, actually they are completely irregular relative to the cam shaft axis as is the driving cam 12'. Offhand, it might be confusing that cams 31 differ in shape from cams 12', although the claw tip traverses the same path in both directions of film feed. This is required, however, by the location and shape of the followers 33 as compared to the followers 22' and 23'. It will be obvious that the two cams 31 and the two followers 33 could be replaced by a single cam and follower placed on either side of the cam 12' and its followers 22' and 23' and still obtain the desired movement for the claw. There are two outstanding advantages derived from the use of two cams 31 and two followers 33, however; one being that the duplication of these parts makes it possible to balance the claw member and shaft to prevent torsional effects from normal operating forces, and the other being that a desirable lateral guiding action for the claw member is readily obtained by the use of the flanges 34 on follower surfaces 33.

Although I have shown and described certain specific embodiments of my invention, I am fully aware that many modifications thereof are possible. My invention, therefore, is not to be limited to the precise details of construction shown and described, but is intended to cover all modifications coming within the scope of the appended claims.

Having thus described my invention, what I claim as new and desire to secure by Letters Patent of the United States is:

1. A cam-operated pull-down mechanism for intermittently advancing a perforated film along a given path and comprising a rotatable peripheral cam whose axis of rotation extends substantially parallel to, and laterally of, the film path, a cam follower having two follower surfaces disposed in acute angular relation to one another and adapted to engage said cam, a claw on said follower for engaging and advancing the film once for each revolution of said cam, means for mounting said cam follower so that it is free to move relative to the film path under control of said cam in directions to move the claw thereon longitudinally and perpendicularly of said film path, means for rotating said cam at a speed to oscillate said claw at a frequency of "n" strokes per minute, and means including a spring normally urging said follower in a direction to hold the two follower surfaces thereof in contact with said cam, said follower and spring-urging means having a natural frequency equal to n oscillations per minute, whereby the working pressure between said cam and follower surfaces, and hence wear on said two parts, is reduced.

2. A cam-operated pull-down mechanism in accordance with claim 1, and characterized by the fact that said cam has a contour no finite portion of which is arcuate with respect to a single center and all adjacent curve portions thereof blend into each other without a sudden change in curvature, whereby the acceleration curve thereof is devoid of sharp corners and sudden changes of large magnitude.

3. A cam-operated pull-down mechanism for intermittently advancing a perforated film along

a given path and comprising a rotatable peripheral cam whose axis of rotation extends substantially parallel to, and laterally of, said film path, a cam follower having two follower surfaces disposed in acute angular relation to one another and adapted to engage said cam, a claw on said follower for engaging and advancing the film once for each revolution of said cam, means for mounting said follower so that it is free to move under control of said cam to move said claw through a closed path to advance the film and has its follower surfaces normally held in contact with said cam and including an arm pivoted at one end on an axis parallel to the cam axis, an extension on said follower pivoted to the other end of said arm, a spring acting on said arm, means for rotating said cam at a speed to oscillate said claw at a frequency of n strokes per minute, said arm, spring and follower combination having a natural frequency of n oscillations per minute, whereby the spring and parts moved thereby are tuned to cancel out the fundamental harmonics and certain portions of the higher harmonics and thereby reduce the working pressure between the cam and follower surfaces.

4. A cam-operated pull-down mechanism according to claim 3, characterized by the fact that said cam includes flanges extending from opposite sides beyond the entire peripheral face thereof, said flanges arranged to engage opposite edges of said follower faces to laterally guide said follower in a given plane of movement.

5. A cam-operated pull-down mechanism according to claim 3, characterized by the fact that said cam has a configuration to impart to the claw a pull-down stroke consuming approximately 130° of rotation of the cam and characterized by a positive acceleration, through approximately one-half of said pull-down stroke followed by negative acceleration through the remainder of the stroke until substantially the end of the stroke where the negative acceleration is gradually reduced to zero at the end of the pull-down stroke.

6. A cam-operated pull-down mechanism according to claim 3, characterized by the fact that the top and bottom edges of the claw are inclined toward one another by substantially 4° from the horizontal, and the cam configuration being such as to cause the claw to enter the film perforation at the top of the stroke with the top edge of the claw substantially horizontal and parallel to the top edge of the engaged perforation and to a depth such that the claw fills said perforation and leaves the perforation at the bottom of the stroke with the bottom edge of the claw substantially horizontal and parallel to the lower or engaged edge of the perforation.

7. A cam-operated pull-down mechanism for intermittently advancing a perforated film along a given path and comprising a rotatable shaft whose axis lies substantially in a plane parallel to that of said film path, a first peripheral cam on said shaft for feeding the film forwardly when the shaft is rotated in the direction of forward movement of the film, a cam follower including a claw thereon for engaging and advancing said film, two follower surfaces on said follower disposed in and adapted to simultaneously engage two spaced points on said cam in all positions of said cam, means for mounting said follower so that it is capable of movement under control of said cam in directions to move the claw thereon longitudinally and perpendicularly of said film path as necessary to intermittent movement of

the film thereby, a spring normally urging said follower toward said cam to maintain both of said follower surfaces in contact therewith at all times, and means for positively preventing said cam follower from jumping off said cam for any reason and for intermittently feeding the film in the opposite direction upon rotation of said cam shaft in the opposite direction.

8. A cam-operated pull-down mechanism for intermittently advancing a perforated film along a given path and comprising a rotatable shaft whose axis lies substantially in a plane parallel to that of said film path, a first peripheral cam on said shaft for feeding the film forwardly when the shaft is rotated in the direction of forward movement of the film, a cam follower including a claw thereon for engaging and advancing said film, two follower surfaces on said follower disposed in and adapted to simultaneously engage two spaced points on said cam in all positions of said cam, means for mounting said follower so that it is capable of movement under control of said cam in directions to move the claw thereon longitudinally and perpendicularly of said film path as necessary to intermittent movement of the film thereby, a spring normally urging said follower toward said cam to maintain both of said follower surfaces in contact therewith at all times, and means for positively preventing said cam follower from jumping off said cam for any reason and for intermittently feeding the film in the opposite direction upon rotation of said cam shaft in the opposite direction, and including a second peripheral cam mounted on said shaft in side-by-side relation with said first cam, a third follower surface fixed to said cam follower substantially opposite the vertex of the angle formed by said first two follower surfaces and in a position to engage said second cam, said third follower surface and second cam relatively disposed to be free from engagement when the first cam and two follower surfaces are operating normally to advance the film in a forward direction and adapted to come into engagement only when said two follower surfaces tend to leave said first cam for any reason and when the shaft is rotated in a direction opposite to that in which it is rotated to advance the film.

9. A cam-operated pull-down mechanism for intermittently advancing a perforated film along a given path and comprising a rotatable shaft whose axis lies substantially in a plane parallel to that of said film path, a first peripheral cam on said shaft for feeding the film forwardly when the shaft is rotated in the direction of forward movement of the film, a cam follower including a claw thereon for engaging and advancing said film, two follower surfaces on said follower disposed in and adapted to simultaneously engage two spaced points on said cam in all positions of said cam, means for mounting said follower so that it is capable of movement under control of said cam in directions to move the claw thereon longitudinally and perpendicularly of said film path as necessary to intermittent movement of the film thereby, a spring normally urging said follower toward said cam to maintain both of said follower surfaces in contact therewith at all times, and means for positively preventing said cam follower from jumping off said cam for any reason and for intermittently feeding the film in the opposite direction upon rotation of said cam shaft in the opposite direction, and including a second peripheral cam mounted on said shaft in side-by-side relation with said first cam, a third follower surface fixed to said cam follower

15

substantially opposite the vertex of the angle formed by said first two follower surfaces and in a position to engage said second cam, said third follower surface and second cam relatively disposed to be free from engagement when the first cam and two follower surfaces are operating normally to advance the film in a forward direction and adapted to come into engagement only when said two follower surfaces tend to leave said first cam for any reason and when the shaft is rotated in a direction opposite to that in which it is rotated to advance the film, and flanges extending from opposite sides of said third follower into overhanging relation with opposite sides of said second cam to laterally guide said two followers to movement in a given plane.

10. A cam-operated pull-down mechanism for intermittently advancing a perforated film along a given path, and comprising a rotatable peripheral cam whose axis of rotation extends substantially parallel to, and laterally of, the film path; a claw arm having a follower surface normally engaging said cam; a claw on said arm for engaging and advancing the film; means for mounting said claw arm so that it is free to move relative to the film path under control of said cam in directions to move the claw longitudinally and perpendicularly of said film path; said cam having a contour no finite portion of which is arcuate with respect to a single center and all adjacent curve portions of which blend into each other without a sudden change in curvature whereby the acceleration curve thereof is devoid of sharp corners and sudden changes of large magnitude.
